UNITED STATES PATENT OFFICE.

JOHN W. BURKETT, OF COLUMBUS, OHIO, ASSIGNOR TO THE BURKETT MANUFACTURING COMPANY, OF COLUMBUS, OHIO, A CORPORATION OF OHIO.

INTERNAL-COMBUSTION ENGINE.

1,225,310.

Specification of Letters Patent.

Patented May 8, 1917.

Application filed December 1, 1916. Serial No. 184,802.

To all whom it may concern:

Be it known that I, JOHN W. BURKETT, a citizen of the United States, residing at Columbus, in the county of Franklin and 5 State of Ohio, have invented certain new and useful Improvements in Internal-Combustion Engines, of which the following is a specification.

This invention relates to internal combustion engines and is more particularly directed to an improved type of valve structure. Specifically, this invention is considered by me as an improvement over a portion of the valve structure shown in my co-pending application, Serial Number 75160.

The main object of this invention resides in a structure whereby a pocket construction is provided into which the intake gases are drawn to prevent unnecessary waste during the normal operation of the engine. The structure is also such that these indrawn gases may be heated before they are introduced into the engine cylinder, thus insuring more perfect vaporization.

25 The preferred embodiment of my invention is shown in the accompanying sheet of drawings, in which similar characters of reference designate corresponding parts, and in which:

30 Figure 1 is a central vertical section through one end of an internal combustion engine showing my improved valve in its applied position, and,

35 Fig. 2 is a horizontal section taken through the intake and exhaust passages as shown in Fig. 1.

In these several views, the engine cylinder is designated by the reference numeral 1, this cylinder being provided with a water 40 jacket 2 and a head portion 3 in which the exhaust port 4 and the intake port 5 are located. Between these two ports or passageways there is formed a common passageway 6, into which the valve structure for 45 the entire engine is mounted. This valve structure comprises a hollow sleeve valve 7 closed at its rear end as shown at 8 and provided at this closed end with a circular rack 9, by means of which it is suitably 50 rotated by mechanism not shown, to uncover the ports 4 and 5 in their proper order. This sleeve valve is also provided with a slotted opening 10, which opening, when positioned opposite either the ports 4 and 5, 55 forms a means of communication between

these ports and the interior of the engine, this communication being governed, however, by the puppet valve 11 shown mounted upon the inner end of a cage member 12. This cage member remains in a stationary position and is provided with ports 13 and 14 lying opposite the exhaust and intake passageways 4 and 5 respectively. It will be noticed that the sleeve valve is mounted between this cage member and the engine head and in this manner cuts off or completes the communication between these passages and the interior of the common passage 6. Within this cage member there is formed a pocket structure by means of the wall 15, this pocket structure being open at its front end as is shown at 16 and being of a size which will prevent the wasting of an unnecessary amount of fuel after the same is drawn therethrough. During the normal operation of the engine, the valve stem 17 of the puppet valve is operated to cause the valve head 11 to open. At this time, the sleeve valve is in such position that its slotted opening 10 will be adjacent either 60 the exhaust or intake passageways 4 or 5. On the intake stroke of the piston, this sleeve valve will lie in a position opposite the passageway 5, thereby establishing communication to the interior of the cage member. The volume of this interior portion of the cage has been materially reduced, however, by the interposition of the wall 15 so that the volume of gas drawn in which does not enter the engine cylinder, will be 65 pocketed within the space beneath the wall 15 so that when the sleeve valve turns to break the communication of the passageway 5, this space is what is known as a dead space. Because of the small volume, there is only a 70 very small portion of the gas which remains in this pocket, but inasmuch as there is only one outlet, a majority of the vapors will remain therein until the intake passageway 5 is again opened. After the firing of the engine, the puppet valve is again opened by mechanism not shown, to allow the escape of the exhaust gases, but because the space beneath the wall 15 is a dead space, these exhaust passages will not commingle with the fuel gases, but will pass directly out through the exhaust passageway 4. The passage of the exhaust gases will also heat up this wall 15, thereby heating the passageway through which the intake gases must pass and in 75 80 85 90 95 100 105 110

2
this manner cause their more perfect volatilization. It will also be noted that the space above the partition wall 15 is larger than that beneath it and this is so arranged 5 because the volume of the gases after they are heated, is considerably more than when they are comparatively cool. Therefore, this allows the free entrance of the comparatively cool gases and also the free entrance of the 10 hot and also expanded gases.

What I claim, is:

1. In an internal combustion engine provided with intake and exhaust passages, a common passage leading into the engine cylinder and communicating with both the intake and exhaust passages, a cage member located within said common passage and provided with a valve seat at its inner end, a hollow valve supported by said cage member movable to bring the engine cylinder into or out of communication with said passages, a pocket structure in said common passage in a position over the intake passage and open at its front end to permit the flow of 20 gases therethrough into the engine cylinder, and a valve working on the valve seat of said cage.
2. In an internal combustion engine provided with intake and exhaust passages, a common passage leading into the engine cylinder and communicating with both the intake and exhaust passages, a cage member 25

located within said common passage and provided with a valve seat at its inner end, a hollow valve supported by said cage member and movable to open or close communication between the engine cylinder and said passages, a pocket wall located within said common passage between said intake and exhaust passages to form a pocket for the incoming gases, and a valve working on the valve seat of said cage. 35

3. In an internal combustion engine provided with intake and exhaust passages, a common passage leading into the engine cylinder and communicating with both the intake and exhaust passages, a cage member located within said common passage and provided with a valve seat on its inner end, a hollow sleeve valve supported on the exterior of said cage member movable to open or close the communication between said passages and the engine cylinder, a pocket wall within said cage member interposed between said intake and exhaust passages and open at its inner end, and a primary valve 40 working on the valve seat of said cage. 45

In testimony whereof I affix my signature in presence of two witnesses.

JOHN W. BURKETT.
